DESIGN FOR A GOLF CLUB HEAD

Howard P. G. Newsome, Memphis, Tenn.

Application April 4, 1939, Serial No. 84,041

Term of patent 14 years

To all whom it may concern:

Be it known that I, Howard P. G. Newsome, a citizen of the United States, residing at Memphis, in the county of Shelby and State of Tennessee, have invented a new, original, and ornamental Design for Golf Club Heads, of which the following is a specification, reference being had to the accompanying drawing, forming a part thereof, in which

Fig. 1 is a rear elevation of a golf club head,
Fig. 2, a section on line 2—2 of Fig. 1,
Fig. 3, a section on line 3—3 of Fig. 1, and
Fig. 4, an end elevation.

I claim:

The ornamental design for a golf club head, as shown.

HOWARD P. G. NEWSOME.
